UNITED STATES PATENT OFFICE.

WILLIAM VALE, OF BIRMINGHAM, COUNTY OF WARWICK, ENGLAND.

FOUNTAIN PEN-HOLDER.

SPECIFICATION forming part of Letters Patent No. 290,820, dated December 25, 1882.

Application filed November 6, 1883. (No model.) Patented in England September 14, 1883, No. 4,401.

To all whom it may concern:

Be it known that I, WILLIAM VALE, a subject of the Queen of Great Britain, residing at Birmingham, in the county of Warwick, England, have invented certain new and useful Improvements in Reservoir or Fountain Pen-Holders or other Writing-Instruments, (for which I have received Letters Patent in Great Britain, No. 4,401, dated September 14, 1883;) and I do hereby declare the following to be a full, clear, and exact description of the invention, reference being had to the accompanying drawings, which form part of this specification.

15 The object of my invention is to construct pen-holders or other writing-instruments containing a reservoir of ink or writing-fluid, which, by a slight rotary movement imparted to the terminal mount of the holder, causes a 20 supply of fluid to flow to the nibs of the pen or writing-instrument, and on the reverse movement of the mount the writing-fluid instantly recedes again to the reservoir.

The reservoir or chamber for containing the 25 writing-fluid consists, essentially, of an elastic or hollow cylinder composed of caoutchouc, india-rubber, or other suitable elastic material, the upper end of which said elastic tube or reservoir is connected to a short length of 30 metal tubing (hereinafter called the "reservoir-mount") closed at its bottom. The said reservoir-mount has an external collar formed at its junction with the elastic tubular chamber, and immediately above the said collar the 35 mount is wormed for a short distance with a slow-threaded screw; and above the wormed part is left plain.

To the lower end of the elastic reservoir the pen-holding mount is attached, and running 40 in the axis thereof a small tube, bent at its end, conveys the writing-fluid from the reservoir to the nibs of the pen. A tubular casing or barrel, screwed internally at its upper end, incloses the elastic reservoir, and connects the 45 top and bottom mounts. The internal screwed part of the barrel or casing takes into or engages with the screw of the reservoir-mount. The terminal cap for operating the reservoir covers and is attached permanently to the reservoir-mount, so that the operating terminal

mount and the reservoir-mount described move together.

The action on propelling the terminal mount of the pen-holder is as follows: On the reservoir or chamber having been supplied with 55 writing-fluid, on propelling the holder, the reservoir-mount is rotated, and advanced axially within the internal screw of the casing, so that the elastic or yielding reservoir is twisted spirally through its entire length to 60 an extent dependent on the amount of propulsion. The effect produced by the twisting described is to reduce the capacity of the reservoir, and consequently to urge or drive forward the writing-fluid through the conveying 65 tube or channel to the nibs of the pen, thereby supplying the said pen with an intermittent quantity of ink as the act of propelling is from time to time repeated. The motion of propelling is limited by the abutment 70 edge of the propeller-mount, and the repelling by a stop on the reservoir-mount coming against the shoulder of the screwed part in the inclosing case or barrel. On rotating the propeller-mount in the reverse way than that 75 as before described, repelling is effected. The twisted and partially contracted caoutchouc tube or elastic is uncoiled or straightened out, resuming its normal state, and in so doing the ink left in the pen (or for refilling the 80 reservoir) instantly recedes or flows up the conducting-tube into the reservoir, as before described. Therefore the pen-holder or writing-instrument both propels and repels at 85 pleasure.

I will now proceed to describe, with reference to the accompanying drawings, the manner in which the same is to be performed.

Figure 1 represents in front elevation, and Fig. 2 in side elevation, partly in longitudinal vertical section, a reservoir or fountain pen-holder constructed according to my invention, the reservoir being filled ready for use. Fig. 3 shows the same in action, the ink in the reservoir being forced therefrom by 90 coiling spirally the chamber or reservoir, as represented. The other Figs. 3^a, 4, 5, 6, 7, 8, 9, and 10 represent the parts separately. Fig. 4 is the outer casing of the holder. Fig. 5 is 95 an elevation of the propelling-cap. Fig. 6 is 100 an elevation of the reservoir-mount.

shows a section of the barrel inclosing the reservoir. Fig. 7 shows in elevation the reservoir with its top and bottom mounts. Figs. 8, 9, and 10 show in section the principal parts 5 separately.

The same letters indicate the same parts in the above figures of the drawings.

a is the reservoir or chamber, composed of caoutchouc or india-rubber, for containing the reservoir of ink or writing-fluid. The upper end, *a*², of the elastic chamber or cylinder *a* is connected to a terminal mount, *b*, closed at its lower end. The mount is wormed externally with a slow-threaded screw, *b*². This reservoir-mount is connected permanently by soldering, or otherwise, to the terminal or operating cap *c*, so that this cap and the mount *b* move together when operating the pen-holder. The lower end, *a*³, of the elastic reservoir *a* is connected to the pen-holding mount *d*, and in the axis of the said mount a tubular channel, *d*², communicates with the reservoir of ink, and through which said channel ink or writing-fluid flows to the nibs of the pen *e*. *f* is a 25 tubular casing or barrel inclosing the elastic or yielding reservoir *a*, and connects the top mount, *b*, and bottom mount, *d*. The said inclosing barrel or casing *f* is screwed internally at *f*², which takes upon or engages with the 30 screw *b*² of the mount *b*. The barrel *f* is surrounded by an external covering, *g*, of vulcanite or other suitable material.

In order to supply the pen with ink or writing-fluid, the action of the parts is as follows: 35 The reservoir or chamber having been supplied with the necessary writing-fluid, on propelling the cap *c*, Fig. 2, the reservoir-mount *b* is rotated and advanced axially down the barrel *f* through a distance proportionate 40 to the amount of propelling by *b*² of the mount *b* worming within the screw *f*² of the barrel *f*, and at the same time the cap *c* is lowered or advanced within the upper end of the barrel, in which end *c*² of the cap *c* slides, thereby 45 diminishing the distance (as in Fig. 3) between the end of the barrel and collar or stop *c*³, which limits the motion of the cap within the barrel, so that in consequence of the mount *b*, attached to the upper end, *a*², of the elastic or yielding chamber, having been turned or rotated several times by the propelling action of the cap (while the lower end, *a*³, of the said reservoir is held stationary) it acts upon the elastic or yielding reservoir, so as to twist it 55 spirally through its entire length, as represented in Fig. 3 of the accompanying drawings. The effect produced by the twisting described and represented is to reduce the internal capacity of the reservoir, and consequently 60 to urge or drive forward the writing-fluid through the channel *d*², and conveying-tube *d*³ to the nibs of the pen *e*, as shown at Fig. 3, and thereby supplying the said pen with an intermittent quantity of ink, as the act of propelling is from time to time repeated. The motion 65 of propelling, and consequently the twist-

ing of the ink-reservoir, is limited by the abutment *c*³ of the cap *c*, while the repelling is limited by the shoulder *b*³ of the mount *b*, coming against the under side, *f*³, of the screwed 70 part *f*², of the inclosing-barrel *f*. On rotating the cap *c* in the reverse way than that as before described, repelling is effected. The twisted and partially constricted caoutchouc or india-rubber tube or reservoir *a*, as in Fig. 75 3, is uncoiled or straightened out, the parts resuming their normal positions, as represented in Figs. 1 and 2, and in so doing the ink left in the pen (or for refilling the reservoir) instantly recedes or flows up the conducting-tube by partially rarefying the reservoir by opening out its folds or coils and increasing its internal area, as shown in Fig. 1, so that ink at the mouth of the conducting-tube recedes up the said tube *d*³ into the reservoir-chamber, as described. Therefore the pen-holder or writing-instrument both propels and repels at pleasure. The cap *h*, Fig. 4, covers the lower mount, *d*, when the pen-holder is not in use. When the flow of ink is required 85 to be made continuous instead of intermittent, as before described, a small hole in communication with the reservoir is uncovered. The refilling is effected by temporarily stopping or closing the said hole in order to rarefy 90 the interior of the ink chamber or reservoir by the raising of the point of the screw *t* out of the seat *u*² of the passage *u*, thereby admitting air to the ink-chamber and causing a continuous flow. On closing the mouth of the hole *u* by the 95 point of the screw and repelling the mount, ink flows back into the reservoir for refilling or otherwise, as shown at Fig. 3^A.

Having described the nature of the said invention, I wish it to be understood that I 100 claim—

1. In a fountain or reservoir pen, the combination, with the exterior casing and the stylus or point, of an elastic reservoir communicating with the said stylus and provided 105 at its end with a movable plunger, whereby it may be compressed and its contents discharged upon or into the stylus, substantially as and for the purpose described.

2. In a fountain-pen, the combination, with 115 an external casing and a stylus, of an elastic reservoir communicating with the stylus and adapted and designed to be twisted and its contents thereby discharged, substantially as described.

3. In a fountain-pen, the combination, with an exterior casing, of an elastic reservoir attached at one end to a stationary mount and at the other end to a movable mount swiveled in the casing, whereby the reservoir may be 125 twisted and its contents discharged, substantially as described.

4. In a fountain-pen, the combination, with the exterior casing and the stylus, of an elastic reservoir communicating with the stylus and attached to a plug screwing into the upper end of the casing, substantially as described. 130

5. In a fountain-pen, the combination of an elastic reservoir, attached at one end to a stationary mount and at the other to a screw-threaded mount, with a stop to limit its movement, substantially as described.

6. In a fountain-pen, the combination, with the exterior casing, of an elastic reservoir provided with a discharging-tube and adapted to be spirally twisted to discharge its contents 10 through said tube, substantially as described.

7. In a fountain-pen, the combination, with the exterior casing and an elastic reservoir having an outlet at one end of said casing, of a movable plunger at the other end of said

casing, adapted to impinge upon said reservoir and cause it to discharge its contents, substantially as described.

8. The combination of casing *g*, mount *d*, outlet-tube *d'*, and elastic reservoir *a*, with the movable screw-threaded plunger *b* and cap *c*, 20 substantially as described.

In testimony that I claim the foregoing I have hereunto set my hand this 15th day of October, 1883.

WILLIAM VALE.
